CONVERTIBLE DRILLING TOOL

Jesse C. Wright, Los Angeles, Calif.

Application December 5, 1934, Serial No. 756,053

4 Claims. (Cl. 255—61)

This invention relates to a drilling tool and relates more particularly to a drill for use in the rotary method of well drilling. A general object of the invention is to provide a simple, practical and improved convertible well drill.

In the drilling of oil and gas wells with the rotary method it is often advantageous to drill a pilot bore of relatively small diameter and then enlarge the pilot bore to the required size. Rapid progress and a straight hole or bore may be obtained by using only a relatively light drilling pressure on the drill making the pilot bore. In enlarging the pilot bore a pilot bit follows the previously formed pilot bore to effectively guide the tool and a heavy drilling or feeding pressure may be put on the bore enlarging cutter without danger of deviating from the vertical. Heretofore it has been the usual practice to employ different or separate tools to drill the pilot bore and to enlarge the pilot bore.

One of the objects of this invention is to provide a well drill that may be used to drill a pilot bore and then employed to enlarge the pilot bore.

Another object of the invention is to provide a well drill that may be readily converted from a tool for drilling a pilot bore to a tool or drill for enlarging the pilot bore.

Another object of the invention is to provide a well drill that comprises a shank having a bit at its lower end adapted to make a pilot bore, and a guide on the shank above the bit for guiding the bit during the drilling of the pilot bore and that may be replaced by a cutter for enlarging the pilot bore.

A further object of the invention is to provide a simple, convenient and dependable means for locking the threadedly connected parts of a well tool against disconnection.

The various objects and features of my invention may be fully understood from the following detailed description of a typical preferred form and application of my invention, throughout which description reference may be made to the accompanying drawing, in which:

Fig. 1 is a side elevation of the drill provided by this invention operating to enlarge a pilot bore illustrating one quarter of the drill in longitudinal cross section. Fig. 2 is a side elevation of the principal lower portion of the drill carrying the guide and drilling a pilot bore, showing one quarter of the drill in longitudinal cross section, and Figs. 3 and 4 are transverse detailed sectional views taken as indicated by lines 3—3 and 4—4, respectively, on Fig. 2.

The well drill of the present invention includes,

generally, a shank 10, a bit 11 on the lower end of the shank operable to drill a pilot bore, means 12 for locking the bit against displacement from the shank 10, a removable guide 13 on the shank 10 and a cutter 14 adapted to replace the guide 13 to enlarge the pilot bore.

The body or shank 10 of the tool is adapted to be connected to the lower end of a drilling string and is designed or constructed to carry the bit 11 and the guide 13 and cutter 14. In practice the shank 10 may be an elongate integral member as illustrated in the drawing. A screw threaded pin 15 or its equivalent is provided on the upper end of the shank 10 to facilitate the connection of the shank 10 with the drilling string. The shank 10 is preferably of round cross section and has an upper portion 16 and a lower portion 17 of reduced diameter. An annular flange 18 is provided on the shank 10 at the lower end of the portion 16. The lower end of the flange 18 forms a downwardly facing thrust shoulder 19. The part of the shank immediately below the shoulder 19 is adapted to carry the guide 13 and the bore enlarging cutter 14 and is provided with a screw thread 20. Means is provided at the lower end of the shank 10 for carrying the bit 11. In the preferred form of the invention a tapered screw-threaded pin 21 is provided on the lower end of the shank 10 to carry the bit 11. The pin 21 is of reduced diameter providing a downwardly facing annular shoulder 22 at its upper end. A central longitudinal fluid passage 23 extends through the shank 10 to conduct the circulation fluid downwardly to the bit 11.

The cutter head or bit 11 is provided to drill the pilot bore B and following this operation is adapted to operate in the pilot bore B to guide the drill when the cutter 14 is enlarging the bore. The bit 11 includes a body or shoe 24 threaded to the shank 10 and locked against detachment therefrom by the means 12. The shoe 24 has a central screw-threaded socket 25 in its upper end to receive the pin 21. The upper end of the shoe 24 is preferably flat to bear upwardly against the shoulder 22. The lower end of the shoe 24 may be conical or tapered downwardly and inwardly as illustrated throughout the drawing. The socket 25 continues below the end of the pin 21 to form or provide a fluid chamber 26 at the lower end of the fluid passage 23.

Means is provided on the shoe 24 to cut or drill the pilot bore B and to later operate in the pilot bore to guide the drill when it is enlarging the bore. The cutting and guiding means is pref-

erably in the form of a plurality of cutting blades 27 projecting from the shoe 24 at circumferentially spaced points. In the particular case illustrated in the drawing there are four equally spaced blades 27. The blades 27 project outwardly and downwardly from the shoe 24 and lie in substantially vertical radial planes. In the preferred construction the blades 27 are of substantial length to have long reaming and guiding edges 28. As shown in Fig. 2 of the drawing the edges 28 engage the side wall of the bore B to ream and smooth it and, as shown in Fig. 1 of the drawing, the edges 28 engage the wall of the bore B to guide the drill while the cutter 14 is enlarging the bore. The lower ends of the blades 27 are provided with cutting edges 29. The cutting edges 29 are curved upwardly and inwardly and the lower portions of the blades 27 are curved forwardly relative to the direction of rotation of the drill. Upwardly extending openings or notches 30 may be provided in the lower ends of the blades 27. The cutting edges 29 are adapted to act on the formation on the bottom of the pilot bore B during the forming or drilling of the pilot bore. The blades 27 extend upwardly to points adjacent the upper end of the shoe 24 and their upper ends are preferably inclined downwardly and outwardly as illustrated in Figs. 1 and 2 of the drawing. Ports 9 are provided in the lower wall of the shoe 24 to discharge the circulation fluid downwardly between the blades 27.

The means 12 for locking the bit 11 on the shank 10 is such that the bit may be tightly and fully threaded on the pin 21 and then securely and dependably locked against unthreading from the pin. In accordance with the broader aspects of the invention the means 12 may be employed to lock various threadedly connected parts of well drilling tools against disconnection, for example, the means may be used to lock sections of a sectional stem or shank against disconnection or may be employed to lock the guide 13 or the cutter 14 against unthreading from the shank 10 of the tool illustrated in the drawing. In the particular well tool being described the means 12 is utilized to prevent disconnection of the bit 11 from the shank 10, it being understood that this typical use or application of the lock means 12 is not to be construed as limiting or restricting the invention.

The lock means 12 includes rigid or fixed parts 31 on one of the members to be locked against disconnection. In the particular case illustrated in the drawing the lock parts 31 are preferably provided on the bit 11. The parts 31 are in the nature of ears or lugs rigidly connected with the shoe 24. The lugs 31 are welded or otherwise fixed to the upper ends of the blades 27 and project upwardly beyond the upper end of the shoe 24. The inner sides of the lugs 31 are shaped to substantially conform to and bear against the upper end portion of the shoe 24. In practice the lugs 31 may be substantially rectangular in transverse cross section and may have their upper ends bevelled or inclined downwardly and outwardly.

The lock means 12 includes tapered or threaded sockets 32 in the shank portion 17 above the shoulder 22. A lock part or screw 39 is adapted to be threaded in a socket 32 to cooperate with a lug 31 to prevent unthreading of the shoe 24 from the pin 21. The screw 39 may be socket headed as illustrated in Fig. 4 of the drawing. It is a feature of the invention that the lugs

31 and sockets 32 are related so that a lug 31 occurs adjacent or immediately behind a socket 32 regardless of the rotative position assumed by the bit 11 when threaded against the shoulder 22. Where there are four blades 27, two lugs 31 may be attached to diametrically opposite blades 27. When the lugs 31 are spaced 180° apart there are three sockets 32, spaced 120° apart as shown in Fig. 4 of the drawing. With this relating of the lugs 31 and the sockets 32 there is an exposed or accessible socket 32 adjacent or immediately in front of a vertical plane defining the front of a lug 31. After the bit shoe 24 has been fully threaded on the pin 21 the screw 39 is threaded in the exposed socket 32 in front of an adjacent lug 31 to prevent unthreading of the shoe from the pin.

The guide 13 is provided to guide the tool during the drilling of the pilot bore B and in accordance with the invention the guide is removable from the shank 10 so that it may be replaced by the bore enlarging cutter 14. The guide 13 includes a tubular body or sleeve 33 having an internal thread 34 for cooperating with the thread 20 on the shank 10. Before the attachment of the bit 11 to the shank 10 the sleeve 33 may be passed upwardly over the lower end of the shank and brought to a position for threading on the shank below the shoulder 19. The upper end of the sleeve 33 is adapted to bear upwardly against the shoulder 19 to limit the threading of the sleeve on the shank and for the transmission of thrusts from the guide to the shank. The sleeve 33 may be of substantially the same diameter as the flange 18 and its lower end may be inclined or bevelled. A plurality of circumferentially spaced grooves 35 is provided in the sleeve 33. The grooves 35 extend downwardly from the upper end of the sleeve 33 and terminate at upwardly facing shoulders 36. In accordance with the invention the side walls of the grooves 35 are channeled or undercut.

Bearing members or guide members 37 are arranged in the grooves 35 and project from the sleeve 33 to cooperate with the wall of the pilot bore B. The members 37 are in the nature of formation engaging pads and have blunt or rounded outer surfaces for contacting with the wall of the bore B. It is preferred to form the guide members 37 of brass or the like so that they may be readily cut or milled away in the event that it becomes necessary to run a fishing tool down over the drill. The guide members 37 are removably locked or retained in the grooves 35. Dove-tailed tongues or flanges 38 are provided on the opposite longitudinal sides of the members 37 to cooperate with the undercut side walls of the grooves 35. The flanges 38 cooperate with the undercut walls of the grooves to positively hold the guide members against outward displacement from the grooves. The lower ends of the guide members 37 engage or rest on the shoulders 36.

In accordance with the invention the act of threading the sleeve 33 to its position on the shank 10 locks the guide members 37 against displacement from the grooves 35. The upper ends of the members 37 are substantially flush with the upper end of the sleeve 33 and thus engage or are immediately adjacent the shoulder 19 when the sleeve is threaded to its final position on the shank. The guide members 37 are proportioned so that their outer active surfaces are spaced approximately the same distance from the vertical center of the drill as the outer guiding edges 28 of the blades 27. During the drilling of the

5 pilot bore B the circumferentially spaced guide members 27 are adapted to engage the formation at the side wall of the bore some distance above the bit 11 to effectively guide the bit to drill a straight vertical bore.

10 The cutter 14 is provided to replace the guide 13 after the drilling of the pilot bore B and is operable to enlarge the pilot bore to the required diameter. The cutter 14 includes a tubular shoe or sleeve-like body 40 having an internal thread 41 for cooperating with the thread 20 of the shank 10. Following the removal of the guide 13 from the shank the body 40 of the cutter 14 is adapted to be passed upwardly on the shank 15 and then threaded in position so that its upper end bears against the shoulder 19. The cutter 14 includes a plurality of spaced cutting parts 42. The cutting parts 42 may be in the nature of blades projecting outwardly and downwardly 20 from the body 40. In the particular case illustrated in the drawing there may be four blades 42. The blades 42 are provided at their lower ends with cutting edges 43. The cutting edges act on the formation at the shoulder S occurring 25 between the pilot bore B and the adjacent enlarged portion of the well W. In practice the cutting edges 43 may be straight and substantially horizontal. The cutting blades 42 are provided with outer edges 44 for reaming or smoothing 30 the wall of the enlarged well W.

35 It is believed that the utility and practicability of the well drill of the present invention will be readily understood from the foregoing detailed description. When it is desired to drill the pilot bore B the guide 13 is passed over the lower end of the shank 10 and threaded on the shank to the position where the upper end of the sleeve 33 bears against the shoulder 19. The shoe 24 of the bit 11 is then threaded on the pin 21. As 40 described above, the lugs 31 and sockets 32 are related so that a lug 31 is located adjacent and rearward of an exposed socket 32 when the shoe 24 is threaded to its final position on the pin 21. The lock screw 39 may be threaded in the said 45 exposed socket 32 in front of the lug 31 to positively prevent unthreading of the shoe 24 from the pin. The drill may then be connected with a drilling string and run into the well in the usual manner. When the drill is rotated and 50 fed downwardly the cutting blades 27 operate to form or drill the pilot bore B. The guide members 31 may contact the wall of the bore B above the bit to drill a straight vertical bore.

55 Following the drilling of the pilot bore B the drill is pulled or removed from the well and the bit 11 is detached from the shank 10. The sleeve 33 of the guide 13 is then unthreaded from the shank and passed downwardly over the lower end of the shank. The body 40 of the cutter 14 is 60 passed upwardly over the lower end of the shank 10 and threaded on the shank to have its upper end bear against the shoulder 19. The bit 11 may then be secured to the lower end of the shank and locked in place by the means 12. It 65 is very desirable to lock the bit 11 on the shank when the tool is employed to enlarge a pilot bore. The pilot bore may be oversized at points and the lower portion of the tool and the bit may whip about at such enlarged points and this 70 whipping action may tend to detach the bit 11

from the shank. The means 12, of the invention, dependably and positively locks the bit 11 against detachment from the shank when the tool is enlarging the pilot bore. The tool or drill is passed or run into the well and rotated and 5 fed downwardly in the usual manner. The pilot bit 11 enters and operates in the pilot bore B while the blades 42 are acting on the shoulder S to enlarge the bore. The edges 28 of the blades 27 engage the wall of the bore B to effectively 10 guide the drill. Because of this function of the pilot bit 11 a heavy drilling or feeding pressure may be applied to the drill during the enlarging of the bore without danger of the drill deviating from the vertical. The drill is thus very rapid 15 and efficient in the drilling of the well. It is to be noted that the present invention provides a well drill in which a single shank and a single pilot bit may be employed in the drilling of a 20 pilot bore and in the enlarging of the bore. 25

Having described only a typical form and application of my invention, I do not wish to be limited or restricted to the specific form and application herein set forth, but wish to reserve to myself any modifications or variations that may appear to those skilled in the art or fall within the scope of the following claims.

Having described my invention, I claim:

1. In a well tool, two threaded sections, one section having spaced openings, spaced 30 projections on the section, the openings and projections being related so that an opening is adjacent a projection when the sections are fully connected, and a lock part adapted to be threaded in said opening to cooperate with said projection 35 to prevent unthreading of the sections.

2. In a well tool, two threaded sections, one section having spaced openings, circumferentially spaced cutting parts on the other section, projections on the cutting parts, the 40 openings and projections being related so that an opening is adjacent a projection in any relative rotative position assumed by the sections, and a lock part adapted to be arranged in said opening to cooperate with said projection to prevent 45 unthreading of the sections.

3. A well drill including a shank having circumferentially spaced openings spaced from its lower end, a bit threaded on the lower end of the shank, circumferentially spaced lugs projecting 50 upwardly from the bit, the openings and lugs being related so that a lug is adjacent an opening regardless of the rotative position assumed by the bit relative to the shank, and a lock part 55 adapted to be threaded into an opening to cooperate with a lug to prevent unthreading of the bit.

4. A well drill including a shank having circumferentially spaced openings spaced from its 60 lower end, a bit threaded on the lower end of the shank, circumferentially spaced cutting elements on the bit, lugs projecting upwardly from the elements, the openings and lugs being related so that a lug is adjacent an opening regardless of 65 the rotative position assumed by the bit, and a screw adapted to be threaded into an opening to cooperate with a lug to prevent unthreading of the bit from the shank.
